UNITED STATES PATENT OFFICE.

WALTER J. FROST, OF KENOSHA, WISCONSIN, ASSIGNOR TO THE BADGER BRASS MANUFACTURING COMPANY, OF SAME PLACE.

DESIGN FOR A BICYCLE-LAMP.

SPECIFICATION forming part of Design No. 32,389, dated March 27, 1900.

Application filed November 17, 1899. Serial No. 737,378. Term of patent 7 years.

To all whom it may concern:

Be it known that I, WALTER J. FROST, a citizen of the United States, residing at Kenosha, in the county of Kenosha, in the State 5 of Wisconsin, have invented and produced a new and original Design for Bicycle-Lamps, of which the following is a specification, reference being had to the accompanying drawings, in which—

10 Figure 1 is a plan view of the lamp embodying my design; Fig. 2, a front elevation; Fig. 3, a plan section taken on the line 3 3 of Fig. 4; Fig. 4, a side elevation; Fig. 5, a rear elevation, and Fig. 6 a cross-section taken on 15 the line 6 6 of Fig. 4.

The leading feature of my design, as shown in the drawings, consists in the generally-spherical conformation of the upper portion of the body or flame-chamber of the lamp, 20 the cylindrical form of the lower portion or generating-chamber of the lamp, which is slightly enlarged at its upper portion, and the gradually-diminishing curved intermediate portion, the lower portion of which is of equal 25 diameter with the upper part of the generating-chamber, while its upper portion is contracted where it joins the spherical body of the lamp.

Referring to the drawings, 10 indicates the 30 body of the lamp, which is spherical in its general contour and has openings at its top and bottom and also at the front and on both sides. Around the opening at the top is located an upwardly and outwardly flaring collar 11, above which is supported a cap 12, of greater diameter, having a flattened edge and raised and rounded center portion suitably ornamented.

The opening at the front of the lamp-body 40 is surrounded by a cylindrical portion 13, having an outwardly-flaring margin 14, carrying the lens 15, and ornamented by perforations 16. The openings at the side of the body are

provided with the usual glass side lenses 16, having their outer surfaces faceted, as shown. 45

The water-reservoir 17 is located at the back of the lamp, its front portion being recessed, as indicated at 18, to conform to the contour of the adjacent portion of the lamp-body, and the body portion of said reservoir is cylindrical and is joined to the flattened rear wall 19 thereof by a curved portion 20.

The lower portion of the lamp or generating-chamber 21 is cylindrical in form, being somewhat enlarged by a bead or fillet 22 at 55 its upper end, and the intermediate portion 23, lying between the lamp-body and the generating-chamber, has an annular lower portion 24, corresponding in shape with the fillet 22 and joined to the body of the lamp by an 60 upwardly and inwardly curved or hollowed portion 25, of upwardly-decreasing diameter. A tube 26, starting from a point closely adjacent to the bottom of the water-chamber, extends obliquely downward to the intermediate portion 23 and thence horizontally to the front of the lamp, its location being central relative to the lamp, as shown in Fig. 6. A supporting-lug 27 is attached rigidly to the generating-chamber at a point immediately 65 below the said tube 26 and is so constructed and arranged that its upper side or edge forms a support upon which the tube rests. 70

I have shown the body of the lamp adjacent to the water-chamber and the upper portion 75 of the intermediate part 23 as ornamented with open-work, while the generating-chamber 21 has an ornamental band of vertical ribs or projections.

I claim—

The design for a bicycle-lamp, substantially as herein shown and described.

WALTER J. FROST.

Witnesses:

IRVINE MILLER,
FREDERICK C. GOODWIN.
